UNITED STATES PATENT OFFICE.

CHARLES B. ALLEN, OF ATLANTA, GEORGIA.

CARBURETOR.

Application filed October 21, 1924. Serial No. 744,995.

It is the purpose of the present invention to provide, in a carburetor, a construction including a vacuum chamber, together with a gasoline or fuel control by which the gasoline line can be sprayed into the vacuum chamber together with a mixture of gasoline and air which thoroughly mixes in the vacuum chamber, and upon the intake stroke of the piston of the engine, this combustible mixture is drawn into the engine cylinders.

The invention comprises further features and combinations of parts to be hereinafter set forth, shown in the drawings and claimed.

15 In the drawings:

Figure 1 is a vertical sectional view through the improved carburetor disclosing the preferred embodiment of the invention, wherein the carburetor now used is dispensed with.

Figure 2 is a vertical sectional view showing an auxiliary carburetor construction in connection with the present form of carburetor, whereby an additional volatilized mixture may be drawn into the intake manifold with the ordinary supply from the carburetor now used.

Referring to the drawings, 1 designates a casing which may be any shape and proportions and is adapted to receive a supply of gasoline indicated at 2, with its level shown at 3. Arranged above the carburetor casing 1 is a globular casing 4 about which the wall of an exhaust manifold 5 is constructed, thereby supplying heat to the wall of the casing 4. The casing 4 defines a combined mixing and vacuum chamber 6 which is operatively connected by means of a tube or pipe 7 with the cylinders of the engine.

40 A suitable air supply pipe 8 is provided. This pipe extends through the top of the carburetor casing 1 and terminates in an inlet end 9 at a point adjacent the bottom of the casing 1 and below the level 3 of the gasoline. The other end of the pipe 8 terminates in a funnel 10 which is provided with a wire fabric or screen covering 11 to preclude dust, dirt and other foreign matter from entering the pipe. This funnel is disposed so that air will enter the pipe 8 and be conducted to a point below the level of the gasoline in the casing 1. The air then percolates through the gasoline with which it becomes saturated and rises in the chamber 12 above the level of the gasoline.

55 The pipe 8 passes through a suitable pack-

ing gland 13 to insure the prevention of the escape of the mixture of air and gasoline. The casing 4 connects with a pipe 14 which passes through a packing gland 15 on the top of the casing 1 and this pipe 14 also has its terminal 16 below the level 3 of the gasoline. The pipe 14 is provided with a fuel valve 17 at a point above the level of the gasoline for adjusting the feed of gasoline, and its operating shaft 18 passes through a suitable packing gland 19 carried by the wall of the casing 1. This operating shaft or rod 18 has an arm 20 to which an operating rod 21 is connected, whereby the fuel valve may be operated. The rod 21 is adapted to terminate in suitable means (not shown) to be located adjacent the instrument-board of an automobile, convenient to a chauffeur or operator, whereby the supply of gasoline may be controlled through the pipe 14 to the mixing or vacuum chamber.

The pipe 14 has an air intake opening or port 22 at a point above the valve 17. This opening or port is provided for the purpose of permitting a mixture of gasoline and air taken from the surface of the level of the gasoline to pass through the pipe 14 into the vacuum or mixing chamber 6.

When the engine is at rest, a substantial supply of the mixture of the gasoline and air is collected in the mixing or vacuum chamber 6. This supply being rich and capable of combustion, upon the initial strokes of the engine piston creating suction in the chamber 6, is drawn off, that is, while the fuel valve on the pipe 14 is closed. As this collected supply diminishes, the subsequent supply drawn into the chamber 6 as a result of the intake strokes of the engine piston gradually becomes weaker and hence too lean for combustion.

However, in using the present type of carburetor, it is not the aim to use up this collected supply until it becomes so weak that it will not ignite. In fact, it is the purpose to open the fuel valve 17 before this collected supply diminishes to such a condition. In this case, the suction created in the chamber 6 by the successive intake strokes, results in a combustible mixture being sprayed into the chamber 6 from which it is drawn into the intake manifold and thence into the cylinders of the engine.

The casing 1 is provided with a suitable gasoline feed pipe 22^a for supplying gasoline to the casing. This pipe 22^a has a valve

22^b, whereby the gasoline may be allowed to enter the casing 1 to a level substantially half the height of the casing. This valve may be controlled by any suitable means 5 (not shown).

In Figure 2, the vacuum chamber is dispensed with and the casing 27 is located upon the pipe line leading to a well known construction of carburetor 23 which connects 10 with the usual intake manifold 24, said pipe line being designated by the numeral 25. In this construction, the level of the gasoline is indicated at 26 and the casing 27 has an air intake pipe 28 extending thereinto and 15 terminating at a point below the level 26 of the gasoline, there being a pipe line or tube 29 entering the casing 27 and connecting the intake manifold 24, as at 30. The pipe line 25 is for the purpose of equalizing the 20 level of gasoline in the casing 27 and in the carburetor, the normal level being as indicated at 26. The supply of air enters the casing 27 and escapes below the level of the gasoline to permit it to be saturated with 25 gasoline and collect in the chamber above the level of the gasoline. This mixture of gasoline and air is drawn through the pipe line 29 into the intake manifold and thence into the combustion chamber of the engine. 30 The pipe 29 has an enlarged globular portion 31 defining a vacuum chamber 32 which corresponds to the chamber 6. However, this enlarged portion may be dispensed with, if so desired.

35 The pipe 7 is provided with a butterfly

said supply of gaseous mixture to compen-
ply and thereby controlling the speed of the
motor. This butterfly throttle valve has an
operating shaft 7^b to which an arm 7^c is
connected. A suitable rod 7^d is connected to 40
the arm 7^c and terminates in any suitable op-
erating means (not shown) to be located ad-
jacent the instrument-board of an automo-
bile convenient to the chauffeur or operator,
enabling the butterfly throttle valve to be 45
actuated for regulating the supply of mix-
ture to the combustion chamber.

The invention having been set forth, what
is claimed is:

A carburetor comprising a casing defin-
ing a fuel chamber and having fuel supply
means connected therewith, a pipe extend-
ing through the top of the casing and ter-
minating short of the bottom thereof and
provided at an intermediate point with a 55
fuel valve having actuating means exterior
to the casing, said pipe constituting a con-
ductor for connection with the intake mani-
fold of an internal combustion engine, and
a second pipe extending through the top of 60
the casing and also terminating adjacent the
bottom thereof, said second pipe having an
angular bend terminating in a funnel to
provide an air supply to the casing, the first
said pipe being provided with a lateral port 65
directly above the plane of the fuel valve.

In testimony whereof he affixes his signa-
ture.

CHARLES B. ALLEN.
